SECTIONAL MOLD

Filed May 2, 1928

3 Sheets-Sheet 3

UNITED STATES PATENT OFFICE.

FRANK ZLATNIK, OF GLOBE, ARIZONA, ASSIGNOR TO GLOBE FOUNDRY & MACHINE CO., OF GLOBE, ARIZONA, A CORPORATION OF ARIZONA.

SECTIONAL MOLD.

Application filed May 2, 1928. Serial No. 274,466.

My invention pertains to sectional molds of metal suitable for making chill castings of a type suitable for liners for rod and ball mills.

To a certain extent it has been the practice in making cast articles in chill molds formed of metal and in making such articles such as liners for rod and ball mills, to have the mold made in sometimes two and sometimes three parts. The top and bottom of the mold in such cases usually have integral side or end walls which interfit. In some of these constructions it is customary to have a separate piece forming a closure for one of the open ends for either the base or top or cover section of the mold. A disadvantage of such type of mold is that when the mold warps or cracks that a large portion of it has to be discarded; as for instance, the whole of the base or the whole of the top or cover section must be discarded, this causing considerable expense in replacement. A disadvantage of such types of molds is in their uneven structure. They warp and crack due to the unequal strains set up in some parts of the mold, causing considerable expense in replacement.

An object of my invention is to construct a mold suitable for making chill castings such as liners for rod and ball mills or the like, and to have such mold made in sections; for instance, it may be considered that I have a separate base and top or cover section and with these I utilize wall pieces which are formed to fit in the side walls of the base and top, thus in effect making a complete mold, the parts being held together in a suitable manner.

A further object of my invention is in hinging the top or cover to one of the removable side walls and securing all or some of the side walls in place with wedges.

A further object of my invention is the construction of a removable gate, this having a sliding shutter which forms in effect part of the side wall on one side of the mold, this gate being designed to rest upon a recess formed in one of the side walls.

A further object of my invention is the construction of a series of fillers which may be placed in the mold to form articles of a lesser size than the full mold, and in connection with these fillers to have a slidible displacing block which may be utilized to pry the fillers and the finished casting loose.

Another object of my invention is constructing a mold so that the gate is the last part fitted, thereby allowing inspection of the mold.

An object of my invention is to construct a mold suitable for making chilled castings, such as liners for rod mills and ball mills or the like, in which all of the parts are simple, durable and cheaply replaced. The construction of my mold is such that each face and angle of the cast is formed by a separate part, whereby there are no unequal strains or distortions set up in the mold, and thereby making a cast true to dimensions.

My invention will be more readily understood from the following description and drawings, in which:

Fig. 1 is a plan view of my invention,

Fig. 2 is a side elevation taken in the direction of the arrow 2 of Fig. 1,

Fig. 3 is a vertical cross section on the line 3—3 of Fig. 1 in the direction of the arrows,

Fig. 4 is a vertical cross section of Fig. 1 on the line 4—4 in the direction of the arrows,

Fig. 5 is a plan of the base,

Fig. 6 is a perspective view of one of the side wall pieces,

Fig. 7 is a view of another side wall piece for supporting the gate,

Fig. 8 is a side wall piece forming the hinge connection for the cover,

Fig. 9 is a side wall piece to be utilized opposite the piece of Fig. 8,

Fig. 10 is a perspective view of the main part of the gate,

Fig. 11 is a perspective view of the sliding shutter for the gate,

Fig. 12 is a perspective view of a form of liner which may be cast in my mold,

Fig. 13 is a perspective view of a mold filler block,

Fig. 14 is a plan view of a modification showing a different manner of hinging the top or cover.

In my invention the base is designated by the numeral 11. This may be considered as having end edges 12, side edges 13, an exterior surface 14 and an interior surface 15. In the construction illustrated the interior surface has a flat edge 16 at each side, and is dished downwardly toward the center as indicated at 17 in Fig. 3.

Extending outwardly from the sides there are two pair of end lugs 18 and two pair of side lugs 19, each of these lugs being pro-

vided with a vertical pin 20 and two of the lugs on one side and two of the lugs on one end are provided with bolt holes 21. It will be noted that the upper surface 22 of these lugs is below the flat surface 16 at the ends of the base. The base is provided with a recess 23 for the base of the core.

The hinge end wall 24 is illustrated particularly in Fig. 8. This has a flat base 25 with slightly downwardly extending bosses 25' to fit on the flat surfaces of the lugs 18 and a corner rabbet 26 which fits over the flat edges 16 of the base. The top 27 is also illustrated as flat, having a rabbet 28 to accommodate the edge of the cover as hereunder set forth.

This hinge end piece has a pair of lugs 29 extending upwardly, such lugs having apertures 30 therethrough through which extends a hinge pintle 31. In addition, these end pieces are provided with bolt holes 32. The flanges 33 form a hinge stop.

The opposite end piece 34 (illustrated particularly in Fig. 9) also has a flat base 35 with downwardly extending bosses 35' and a flat top 36, the base having a rabbet 37 to fit over the flat edge 16 of the base of the mold and the top surface also having a rabbet 38 to accommodate the cover of the mold. It will be noted that the inside faces 39 of the hinge end 24 and the end piece 34 are inclined inwardly and upwardly (note Fig. 3) and that the outside surface 40 is vertical and straight.

The side wall section 41 (shown particularly in Fig. 6) has a flat base 42 with downwardly extending bosses 42' to fit on the lugs 19 at one side and has a straight and vertical outer surface 43. The top 43' has a rabbet 44 to accommodate the cover as hereunder set forth. There is an inwardly extending boss 45 which is shaped on its lower edge 46 to conform to the shape of the inside surface 17 of the base of the mold and the top surface 46' is shaped to fit the inside of the cover. The ends 47 are shaped to fit against the inside faces 39 of the hinge end piece 24 and the opposite end piece 34.

The ends of the side wall 41 have a cut-out section 48 for use of a pry bar in prying these sections off to open the mold. This end wall piece is also provided with bolt holes 49. There is a recess 50 formed in the boss 45, this having a displaceable wedge block 51, such block having a curved cut-out section 52 for insertion of a prying tool for a purpose hereunder set forth.

The gate supporting side wall designated generally by the numeral 53 (illustrated particularly in Fig. 7) is somewhat the general shape of the opposite side wall 41. This has a flat base 54 with downwardly extending bosses 55 to fit on the lugs 19 of the base. This piece has a side face 56 which bears against the ends of the end pieces 24 and 34. It is also provided with a boss 57 fitting in

the mold the same as the boss 45. There is also a cut-out section 48 forming a space for a pry bar. The outside face 58 is straight and flat. There is a large recess 59 forming a seat for the gate, extending through this side wall member 53 from the boss 57 to the outer face.

A strengthening member 60 is formed below the base 54 and is designed to fit between the lugs 19. There is also a strengthening shelf 61 extending outwardly with a retaining clip 62 attached to the outer face of such shelf, this being adapted to hold the gate in place. The upper surface of the recess 59 is slightly inclined inwardly and downwardly as indicated at 63 (note Fig. 4).

The mold pieces so far described are assembled by placing the base 11 on a suitable floor and placing the hinge end piece in place and the side piece 41 in place.

These, if desired, may be secured by bolts passing through the bolt holes 32 in the hinge piece 24 and in the lugs 21, and the bolt holes 49 in the side piece 41, and the bolt holes 21. However, such bolts are not really necessary and even if bolts are used it is desirable to insert wedges 64 wedging between the vertical pins 20 and the outer face of the hinge wall 24 and the side wall 41 (note Figs. 1 and 2). The other wall pieces comprising the end piece 34 and the side piece 53 to accommodate the gate are then placed in position resting on the lugs 19 and 18 respectively, and these are secured in position by wedges 64.

The top or cover, designated generally by the numeral 65, is formed with an under surface 66 to conform to the shape of the article being cast; and in the present instance has a slight convex curve from each side forming a reverse 67. This inner face conforms to the shape of the upper surface 46' of the boss 45. At one side there is a vertical recess 68 which preferably has a vertical face 69 parallel to the side face 70 of the top and vertical right-angular faces 71 extending from the face 69 to the face 70.

The top also has a tapered opening 72 which is adapted to accommodate the core 73 of any desired shape, the lower end of this core fitting in the recess 23 in the base 11 (note Figs. 3 and 4). There are also hinge arms 74 extending from one end of the cover and having openings to fit on the hinge pintle 31.

The gate designated generally by the numeral 75 is illustrated in particular in Figs. 1, 4, 10 and 11. This gate has a bottom face 76 adapted to conform to the surface 63 of the recess 59. It also has a rear wall 77 and two side walls 78. These side walls have a cut-out section 79 leaving horizontal shoulders 80.

It will thus be seen that there is no fixed wall for the side of the gate 81 which fits ad-

jacent the mold. The gate is open at the top as indicated at 82 across its whole measurements. The inside bottom surface 83 of the gate may be sloped as indicated in Fig. 4.

5 A sliding shutter 84 (illustrated in particular in Fig. 11) is formed of a flat piece of metal having vertical side faces 85 which fit in the faces 71 of the cover. One of the faces 86 of the sliding shutter fits against the face 69 of the cover thus forming a close fit. The face 87 fits in the cut-out section of the main portion of the gate against the edges 88.

10 The shutter has a cut-out section 89 at the bottom which leaves depending legs 90 on each side, such legs resting on the shoulders 80 at the bottom of the cut-out section 79 of the main portion of the gate. There are lateral lugs 91 at the top of the sliding shutter adapted to facilitate insertion and removal 15 of such shutter. Before fitting of the gate it is preferable to clamp the base and the cover of the mold by engaging a suitable clamp underneath the base and on the flattened surface 92 of the cover.

20 25 By this construction it will be seen that the mold can be built up with the base, removable side walls and the cover hinged to one of said walls, and such cover may be closed, then the core may be fitted leaving a relatively large opening before fitting of the gate, this opening being in the recess 59 in the gate supporting side wall 53. Therefore the operator can examine the interior of the mold and see if it is in proper condition for pouring. The 30 35 main portion of the gate is then fitted in place and after this is properly positioned the sliding shutter is thrust downwardly into place, thus forming a complete mold.

40 45 The type of liner made by the mold above described is illustrated in Fig. 12, being designated by the numeral 92'. It will be seen that this has a curved surface 93 which is adapted to conform to the cylindrical shape of a rod or ball mill, and it has end edges 94 at right angles to the curved surface 93. The side edges 95 are beveled and the top surface 96 has two convex curves meeting in a ridge 97. The core leaves a hole 98.

50 55 In some cases in opening up the mold the cast liner sticks in the mold and if such is the case it may be pried loose by inserting a wedging or prying tool in the curved portion 52 of the displacing wedge block 51 and thrusting this block slightly outwardly from the recess 50 in which it fits on the boss 45 of the side wall piece 41.

60 65 It is customary in making liners to have these of two or more different sizes, and to make smaller sizes than those shown a filler block designated generally by the numeral 99 and shown particularly in Fig. 13, may be inserted. This filler block is illustrated as having vertical opposite sides 100 to fit against the face of the boss 45 and to form an inside end wall of the mold. The lower surface 101

is shaped to conform to the shape of the base of the mold and the top surface 102 to conform to the shape of the top of the mold (note Fig. 4). The ends 103 conform to the inside faces 39 of the hinge end wall 24 and the opposite end wall 34.

70 75 In Fig. 14 I illustrate an alternative construction in which the hinge side wall 105 is opposite the wall 106, having a gate 107 therein. In this case the other blocks are made substantially the same as in the figures above described in order to form a mold having the base and the cover with the four removable sides.

80 85 From the above description it will be noted that a characteristic feature of my invention is that the mold is made up of a multiplicity of parts and that the base and the cover may be considered as substantially flat main sections and that to co-operate with these and to form the closed mold there are the two side and two end pieces which when held in place and with the gate also in position form a closed mold. Therefore, if any of these parts become marred in use, warp or crack, it is only necessary to renew the piece which is defective instead of as in the prior art requiring substantially the replacement of the main structural elements of the mold.

90 95 Various changes may be made in the principles of my invention without departing from the spirit thereof, as set forth in the description, drawings and claims.

I claim:

1. A sectional mold having a base, a cover, a series of removable side wall pieces, and a gate resting on one of said side wall pieces.
2. A sectional mold having a base, a cover, a series of side wall pieces supporting the cover above the base, said pieces being removable, and a gate supported by one of said side wall pieces.
3. A sectional mold comprising in combination a base, a series of lugs connected thereto, a cover, a series of sectional walls supported on the lugs and forming a support for the cover, a gate mounted on one of the side walls, and means on the lugs to wedge the sectional side walls in position.

- with at least one of the sectional side walls having a rabbet adjacent its inside face, such rabbet forming a support for one side of the cover.
- 5 7. A sectional mold comprising in combination a base, a cover, and a pair of side wall sections each having an inwardly extending boss to support two sides of the top, one of said side wall sections having a recess and 10 a gate mounted in said recess.
8. A sectional mold as claimed in claim 7, the gate being formed in two parts and having a sliding shutter, said shutter fitting partly in said recess in alignment with the 15 boss.
9. A sectional mold as claimed in claim 7, two of the end wall sections having a rabbet in the upper edge to engage the cover and form a support, and having a rabbet adjacent 20 the lower edge to fit on the said base.
10. A sectional mold having a base with a plurality of lugs extending outwardly from each of the sides, a plurality of sectional side walls each having bosses on the lower surface 25 to bear on said lugs, pins on the lugs, wedges between the side walls and the pins, and a gate supported on one of the sectional side walls.
11. A sectional mold as claimed in 10, the 30 sectional side wall supporting the gate having a recess from its outer face to its inner face, the gate resting in said recess, means to engage the outer wall of the gate, the said cover having a cut out section and a sliding shutter 35 for the gate fitting in said cut out section.
12. A sectional mold comprising in combination a base, a cover, a series of removable side wall sections, one of said sections forming a hinge connection for the cover, said side 40 wall sections being mounted on the base and forming a support for the cover, and a gate supported on one of the side wall sections and having an engagement on one side with a 45 cut out section of the cover.
13. A sectional mold as claimed in claim 12, the base having a series of lugs extending outwardly therefrom, the side wall sections being supported on the lugs, pins on the lugs, and wedges fitted between the pins and the 50 side wall sections.
14. A sectional mold comprising in combination a base, a plurality of sectional side walls detachably mounted on the base, a cover hinged to one of said side walls, said cover being supported on said walls, the base having 55 a recess therein and the cover having an opening, a core fitted in the opening of the cover and engaging the recess of the base, one of said side walls having a recess from its 60 outer to its inner face leaving a large open-
- ing for inspection of the closed mold, and a gate adapted to fit in said recess and having a closure with the said top or cover.
15. In a sectional mold having a base, a cover, and a series of sectional side walls 65 removably mounted on the base and forming a support for the cover, one of the side walls having a recess with a displaceable wedge block mounted therein, said block having means to engage same with a prying tool to 70 separate a casting from a mold.
16. In a sectional mold a base, a cover, a plurality of sectional side walls mounted on the base and forming a support for the cover, one of said side walls having a boss with a 75 recess, a slidable wedge block mounted in the said recess and having means to engage a prying tool therewith, and a filler block positioned in the mold adjacent the said boss and adapted to be displaced by the said wedge 80 block in the opening of the mold.
17. In a sectional mold a base, a cover, a plurality of sectional side walls mounted on the base and supporting the cover, one of said side walls having a recess from its outer to its 85 inner face forming a large opening for inspection of the mold, and a gate formed in two parts, one of said parts having a base, an outer and two side walls fitted in the said recess and a sliding shutter mounted on the 90 open side of the gate and positioned against one side of the cover.
18. A sectional mold comprising in combination a base, a cover, a plurality of sectional walls mounted on the base and forming a support for the cover, one of said walls having a pair of lugs with apertures therein, a hinge pintle fitted in said apertures, hinge arms on the cover engaging the pintle, and a gate mounted in a recess on one of the side walls 100 and having a closure against one side of the cover.
19. A sectional mold as claimed in claim 18, the base having a recess in its upper surface, the cover having an opening and a tapered 105 core fitted in said opening and engaging the said recess.
20. A sectional mold comprising in combination a base, a cover, and four wall sections detachably supported on the base and forming a support for the cover, one of said walls having a recess with a gate fitted therein and supported on such wall, a pair of the walls having a cut-out section for insertion of a pry bar to pry the walls away from the base and 110 the cover.
- In testimony whereof I have signed my name to this specification.

FRANK ZLATNIK.
